DESIGN FOR A HEARING AID APPARATUS CASE

Douglas H. King, Short Hills, N. J., assignor to
Bell Telephone Laboratories, Incorporated, New
York, N. Y., a corporation of New York

Application August 22, 1942, Serial No. 107,995

Term of patent 14 years

To all whom it may concern:

Be it known that I, Douglas H. King, a citizen
of the United States residing at Short Hills, in
the county of Essex and State of New Jersey,
have invented a new, original, and ornamental
Design for a Hearing Aid Apparatus Case, of
which the following is a specification, reference
being had to the accompanying drawing, forming
a part thereof, in which,

Fig. 1 is a perspective view of a hearing aid
apparatus case showing my new design;

Fig. 2 is a side elevational view;

Fig. 3 is a top plan view; and

Fig. 4 is a bottom plan view thereof.

I claim:

The ornamental design for a hearing aid ap-
paratus case, as shown.

DOUGLAS H. KING.
